(57) **CLAIM**

The ornamental design for a rear combination lamp for an automobile as shown and described.

DESCRIPTION

FIG. 1 is a perspective view of a rear combination lamp for an automobile in accordance with our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The inside surfaces and mounting surfaces of the rear combination lamp, shown in broken lines in FIGS. 1-7, form no part of the claimed design since these surfaces are hidden when the rear combination lamp is mounted to the automobile.
